CLAIM

The ornamental design for a retractor, as shown and described.

DESCRIPTION

FIG. 1 is a front perspective view of a retractor showing our new design.

FIG. 2 is a front elevational view thereof.

FIG. 3 is a rear elevational view thereof.

FIG. 4 is a right side elevational view thereof.

FIG. 5 is a left side elevational view thereof.

FIG. 6 is a top plan view thereof.

FIG. 7 is a bottom plan view thereof.

FIG. 8 is a cross-sectional view thereof, taken along line 8-8 of FIG. 2; and,

(Continued)

FIG. 9 is a perspective view thereof, showing the retractor in use after being inserted into a chest or an abdomen from a small incision, the retractor being deformed in a ring shape in a body, so as to keep the opened part in the opened state. The broken lines illustrate environmental structure and form no part of the claimed design.
